PIECE-END SEWING MACHINE

Irving F. Webb, Elizabeth, N. J., assignor to The
Singer Manufacturing Company, Elizabeth,
N. J., a corporation of New Jersey

Application July 1, 1933, Serial No. 678,562

10 Claims. (Cl. 112—2)

This invention relates to sewing machines of the railway type adapted for sewing together the ends of long lengths of material preparatory to material processing operations, such as practiced in various textile and similar industries, which operations involve the passage of the material over more or less intricate systems of guide rollers making it necessary that the various pieces or lengths of material to be processed be joined together end-to-end so that their passage over the various guide rollers of the processing machinery may be expedited without damage to the faces of the rolls or to the material itself.

The present invention has for an object to provide a piece-end sewing machine of the railway type which is of simplified construction and which is so constructed and arranged as to avoid interference with and facilitate the handling of the heavy rolls of material presented for the joining of their starting ends to the trailing ends of previously presented and unwound rolls.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is an end elevation of a railway sewing machine embodying the invention. Fig. 2 is a front elevation of the machine. Fig. 3 is a similar view on an enlarged scale. Fig. 4 is a rear elevation of the machine on the same scale as Fig. 3. Fig. 5 is a top plan view of the machine. Fig. 6 is a section on the line 6—6, Fig. 5. Fig. 7 is a fragmentary section on the line 7—7, Fig. 4. Fig. 8 is a section on the line 8—8, Fig. 4, and Fig. 9 is an elevation of the sewing machine feeding mechanism.

In the preferred embodiment of the invention, as illustrated, a pair of similar standards 1, rising from the floor 2, carry guide rollers 3 over and under which the fabric 4 to be processed is drawn in the usual manner. Mounted on and projecting forwardly from the spaced standards 1 are the parallel horizontal rails 5 of L-section supported at their forward ends by the rearwardly and downwardly inclined braces 6 secured to the respective standards 1.

Mounted for travelling movements over the rails 5 are the grooved supporting wheels 7, 7 at the opposite ends of a bridge B constituted by a pair of horizontal and parallel L-section rails 8

connected by spacers 9 and cross-braces 10, and strengthened against sagging by underslung truss-rods 11. Guard-rails 12 extending over the wheels 7 and into the grooves of the latter are preferably provided to prevent the possibility of the wheels 7 of the bridge leaving the rails 5. The guard-rails 12 are secured at their rearward ends to the respective standards 1 and are curved downwardly at their forward ends and secured to the respective rails 5.

Adapted to freely run along the parallel, horizontal bridge rails 8 is the sewing machine carriage 13, the grooved wheels 14 of which are journaled on ball-bearings 15, Fig. 4, and rest upon the rails 8. The carriage 13 has mounted thereon a sewing machine A, preferably of the well known Singer Class 81—24 single-thread overedge stitching type. The present sewing machine has a main-shaft 16 carrying the tight and loose belt-pulleys 17, 18, respectively. The sewing machine also has the usual upper reciprocating needle 19, Fig. 3, non-threaded overedge looper 19', presser-foot 20, four-motion feed-dog 21, cloth-plate 22, and edge-trimming knife 23.

An electric motor M for driving the sewing machine is also mounted on the carriage 13 and has its driving pulley 24 connected to the pulleys 17, 18 of the sewing machine by means of the belt 25.

Fulcrumed on the screw 26, Figs. 4 and 7, fast to the ear 27 on the carriage 13 is the belt-shipper lever 28 carrying at its rearward end the spaced upstanding belt-guiding pins 29 and bent upwardly at its forward end to constitute a handle 30. Screwed to and depending from the belt-shipper lever 28 is a bracket 31 carrying a vertically slidable and downwardly spring-pressed plunger 32 the lower end of which is beveled as shown at 33, Fig. 4. A spring 34 connects the bracket 31 with the carriage 13. This spring constantly urges the belt-shipper lever in a direction to shift the belt 25 onto the loose pulley 18 and stop the operation of the sewing machine.

When the belt-shipper lever 28 is manually shifted from full line or "off" position, Fig. 5, to dotted line or "running" position, to start the sewing machine, it is retained in running position by the shoulder 35' of the latch-lever 35 which is fulcrumed on the screw 36 on an ear 37, Fig. 4, of the carriage 13. The tail 35" of the latch-lever 35 is bent up sidewise and stands at an inclination to the vertical, as shown in Fig. 4. The tail of the latch-lever 35 is relatively heavy and tends to drop under the influence of gravity and raise the shoulder 35' to locking or

110

full-line position, Fig. 8, when the belt-shipper lever 28 is manually shifted to running position.

There is preferably clamped upon one of the bridge rails 8, near the end of the bridge from 5 which the sewing starts, a slotted block 38 from which rises a stop-pin 39 in the path of travelling movement of the spring-pressed plunger 32 carried by the belt-shipper lever 28. The purpose of this stop is to aid the operator in positioning the sewing machine A and its carriage 13 in starting position, preparatory to a sewing operation. The work to be stitched is then manually introduced under the presser-foot 20 and the belt-shipper lever 28 is shifted to running position. This shift of the belt-shipper lever carries the spring-pressed plunger 32 to one side of the stop-pin 39, as shown in dotted lines, Fig. 7, and frees the carriage 13 from the stop-pin.

There is also preferably secured to the same 20 rail 8 which supports the stop 39 a second slotted block 40 carrying a stop-pin 41 and a tripper 42 the rounded upper end 43 of which is in the path of travelling movement of the tail of the latch 35 and shifts the latch to dotted line position, 25 Fig. 8, at the end of a sewing operation to stop the machine; the stop-pin 41 being engaged by the spring-pressed plunger 33 and preventing overrunning or coasting of the carriage 13 materially beyond seam-finishing position. The 30 stop-blocks 38 and 40 are adjustable longitudinally of their supporting rail 8 to suit the width of the particular fabric ends to be stitched together. Of course, the latch 35 may be tripped by hand if it is not desired to use the automatic 35 tripper 42.

The feeding mechanism of the sewing machine is of known construction and includes the feed-bar 44, Fig. 9, which is pivotally mounted at 45 on the feed-rocker 46 and is connected by the 40 short-pitman 47 to the feed-lift eccentric 48. The feed-advance eccentric 49 is connected by the pitman 50 to the bell-crank lever 51, 52, fulcrumed at 53 on the machine frame. The arm 52 of the bell-crank lever is provided with a 45 curved and undercut slot or guideway 54 for a slide-block 55 connected to the lower end of a link 56, the upper end of which is connected at 57 to an arm 58 of the feed-rocker 46.

In the present instance there is provided a 50 manually operable device, closely associated with the handle 30 of the belt-shipper lever 28, enabling the operator to conveniently shorten the initial stitches made by the machine. To this end the slide-block 55 is connected by a short 55 link 59 to one end 60 of a slide-rod 61 mounted in a guide-lug 62 secured to the frame of the sewing machine A and having a handle 63 rising from its other end. The starting handle 30 and the feed-shortening handle 63 are both within 60 the simultaneous grasp of one of the operator's hands. In starting the machine, the operator grasps the handles 30 and 63 simultaneously and shifts the handle 30 to dotted line position, Fig. 5; at the same time shifting the handle 63 toward the handle 30 to start the sewing machine with a short stitch. After the sewing has progressed the desired distance, say an inch or two, the handles are released and the recovery spring 64, surrounding the slide-rod 61, Fig. 9, returns 65 the slide-rod 61 and slide-block 55 to initial position, restoring the stitch-length adjustment to its original position for the normal sewing of the seam. As the seam is nearing completion the handle 63 may again be readily manipulated to 70 shorten the stitch for the last inch or two of 75

the seam. While provision is thus made for starting and finishing the seam with a short stitch, it is to be understood that this need only be done in case the particular material being stitched requires it. The seam may be as readily sewn with a uniform stitch-length throughout; the machine being instantly responsive to the will of the operator in this respect.

The two ends of material to be stitched together are brought up in front of the bridge rails 8, as shown in Fig. 1 and impaled in overlapping relation upon the pins 65 carried by blocks 66 mounted on and adjustable longitudinally of the horizontal bar 67 carried by posts 68 rising from the front bridge-rail 8. As best shown in Fig. 6, the impaling pins 65 carried by each block 66 rise from a horizontal arm 69 secured at one end to the block and closely overhanging the sewing machine cloth-plate 22. Sheet-metal guards 70 overhang the impaling pins 65, as shown in Figs. 2 and 3.

The incoming length of material may be in the form of a heavy roll 71, Fig. 1, on a shaft 72 resting upon suitable supporting means 73 rising from the floor 2. It is desirable that these heavy 100 rolls 71 be handled by means of a crane and deposited vertically upon the supporting means 73 in unreeling position. To clear the vertical space above the supporting means 73 for the incoming roll 71, the entire bridge structure B carried by the wheels 7 may be readily shifted to dotted line position, Fig. 1, where it will not interfere with the convenient handling of the incoming roll. After the roll has been deposited in unreeling position, the bridge structure may 110 be pulled forwardly to sewing position wherein the sewing machine and its controls, as well as the material-end supporting and positioning devices are within the convenient reach of an operator stationed in front of the roll 71.

The sewing machine A is preferably adjusted to sew a loose stitch so that the initially overlapping edges of material may be opened out and drawn down into a common plane, as will be readily understood by those familiar with the 120 operation of an overedge sewing machine.

The motor M may be started and stopped by manipulation of a conventional toggle-switch S mounted on the carriage 13 and wired in circuit with the motor and its current supply cord L suitably supported from above.

It is to be understood that the action of the sewing machine four-motion feeding mechanism upon the material propels the carriage 13 along the bridge B.

After a sewing operation is completed the sewing machine is returned manually to its starting position; the inclined end 33 of the spring-pressed plunger 32 riding over the top of the stop-pin 39. The joined ends of material are removed from the impaling pins 65 and the fabric unreeling mechanism is started; the sewing machine and its supporting bridge being pushed over to dotted line position, Fig. 1, where it is out of the way of the next incoming roll of material 135 to be dropped by a crane into the usual supporting means 73.

The invention is not to be understood as limited to the specific embodiment thereof chosen for the purposes of the present disclosure.

Having thus set forth the nature of the invention, what I claim herein is:—

1. The combination with a system of parallel fabric unreeling guide rollers and means for supporting the incoming piece of material to be proc- 150

- essed, of a bridge-member supported at its opposite ends only above said material supporting means, a pair of parallel rails extending lengthwise of said bridge-member, a free wheeled carriage mounted to run on said rails, a sewing machine and a driving motor mounted on said carriage, said sewing machine having stitch-forming and work-feeding mechanisms and being otherwise free at all times to run along said rails, 5 and manually controlled means on said carriage for establishing and interrupting driving relation between the driving motor and the sewing machine.
2. The combination with a motor driven sewing machine having stitch-forming mechanism including a reciprocating needle and feeding mechanism including a work-engaging feeding member, of a free-wheeled carriage supporting said sewing machine for movement in the direction of feed thereof, a bridge member having a trackway extending longitudinally thereof for said wheeled carriage, and means at the opposite ends of said bridge member for supporting the latter for bodily movement transversely of its 25 length.
3. The combination with fabric unreeling guide rolls, of supporting means at the opposite ends of said guide rolls, a bridge carried at its opposite ends by said supporting means, a railway extending lengthwise of said bridge, a wheeled carriage mounted to run freely back and forth along said railway, and a motor-driven sewing machine mounted on said carriage and including stitch-forming and work-feeding mechanisms arranged to operate in the direction of length of 30 said bridge.
4. The combination with fabric unreeling guide rolls and supporting means at the opposite ends of such rolls, of a bridge member parallel to said rolls, a railway running lengthwise of said bridge member, a wheeled carriage on said railway, a motor driven sewing machine including stitch-forming and work-feeding mechanisms and a cloth-plate, said sewing machine being mounted 40 on said carriage with the line of feed of the machine parallel to said railway, a fabric-supporting rail mounted on said bridge member and extending lengthwise of the latter, and fabric impaling pins mounted on said fabric-supporting rail and overhanging the path of travel of said cloth-plate.
5. The combination with fabric unreeling guide rolls and supporting means at the opposite ends of such rolls, of a bridge member parallel to said rolls, a railway running lengthwise of said bridge member, a wheeled carriage on said railway, a motor driven sewing machine including stitch-forming and work-feeding mechanisms and a cloth-plate, said sewing machine being mounted 55 on said carriage with the line of feed of the machine parallel to said railway, a fabric-supporting rail mounted on said bridge member and extending lengthwise of the latter, blocks mounted on and adjustable longitudinally of said fabric-supporting rail, and fabric impaling pins mounted 60 on said blocks.
6. The combination with fabric unreeling guide rolls and supporting means at the opposite ends of such rolls, of a bridge member parallel to said
- rolls, a railway running lengthwise of said bridge member, a wheeled carriage on said railway, a motor driven sewing machine including stitch-forming and work-feeding mechanisms and a cloth-plate, said sewing machine being mounted 70 on said carriage with the line of feed of the machine parallel to said railway, a fabric-supporting rail mounted on said bridge member and extending lengthwise of the latter, blocks mounted on and adjustable longitudinally of said fabric-supporting rail, fabric impaling pins mounted on said blocks, and guards mounted on said blocks and overhanging said impaling pins.
7. In a railway sewing machine, the combination with a railway and a wheeled carriage mounted thereon, of a motor driven sewing machine mounted on said carriage and including stitch-forming and work-feeding mechanisms, feed-adjusting means including a feed-controlling handle travelling with said carriage, and means for starting and stopping the sewing machine including a start- and stop-control handle travelling with said carriage, said handles being juxtaposed for simultaneous operation by one of the operator's hands.
8. In a railway sewing machine, the combination with a railway and a wheeled carriage mounted thereon, of a sewing machine mounted on said carriage and including stitch-forming and work-feeding mechanisms, a main-shaft, and 105 tight and loose belt-pulleys on said main-shaft, a motor on said carriage, a belt connecting said motor to said pulleys, a manually operated belt-shipper mounted on said carriage, and feed-changing means within reach of the operator's 110 hand for manipulation simultaneously with the belt-shipper.
9. In a railway sewing machine, the combination with a railway and a wheeled carriage mounted thereon, of a sewing machine mounted on 115 said carriage and including stitch-forming and work-feeding mechanisms, a main-shaft, and tight and loose belt-pulleys on said main-shaft, a motor on said carriage, a belt connecting said motor to said pulleys, a manually operated spring 120 returned belt-shipper mounted on said carriage, a latch for holding said belt-shipper in machine driving position, and means on said railway for automatically tripping said latch.
10. In combination, means for supporting a 125 roll of fabric to be unreeled, fabric unreeling guide rollers, supporting means at the opposite ends of said guide rollers, a bridge member disposed above and extending lengthwise the axis of the roll of fabric to be unreeled and having a railway running lengthwise thereof, a wheeled carriage free on said railway, a motor driven sewing machine on said carriage and including stitch-forming and work-feeding mechanisms, and means at the opposite ends of said bridge member for supporting the latter, said means including rails disposed transverse to the direction of length of the bridge member and along which the bridge member may be shifted sidewise to clear the space directly above the space to be 130 occupied by an incoming roll of fabric to be unreeled.

IRVING F. WEBB.
